(57) CLAIM

I claim the ornamental design for a garment hanger, as shown.

DESCRIPTION

FIG. 1 is a perspective view of a garment hanger of the design;

FIG. 2 is a top plan view thereof;

FIG. 3 is an end view thereof with the opposite end being a mirror image;

FIG. 4 is an upper perspective view of a second embodiment of my invention;

FIG. 5 is a lower perspective view of a second embodiment of my invention;

FIG. 6 is a top plan view of a second embodiment of my invention;

FIG. 7 is a side plan view of a second embodiment of my invention with the opposite side being a mirror image;

FIG. 8 is a bottom plan view of a second embodiment of my invention; and,

FIG. 9 is an end view of a second embodiment of my invention with the opposite end being a mirror image.

The claimed design is shown broken away to show indeterminate length.
